UNITED STATES PATENT OFFICE.

SIMON S. WHITAKER, OF VENETIA, PENNSYLVANIA.

CUT-OFF VALVE FOR ROTARY ENGINES.

SPECIFICATION forming part of Letters Patent No. 739,566, dated September 22, 1903.

Application filed February 3, 1903. Serial No. 141,678. (No model.)

To all whom it may concern:

Be it known that I, SIMON S. WHITAKER, a citizen of the United States, residing at Venetia, in the county of Washington and State of Pennsylvania, have invented a new and useful Improvement in Cut-Off Valves for Rotary Engines, of which improvement the following is a specification.

This invention relates to certain new and useful improvements in rotary engines, and particularly to a cut-off valve connected thereto; and the invention consists in the certain details of construction and combination of parts, as will be fully described hereinafter.

The present invention is an improvement on the rotary engine described and claimed in Letters Patent issued to me, dated December 23, 1902, No. 716,503.

In the accompanying drawings, Figure 1 is a transverse vertical section through my improved rotary engine and cut-off valve, the same being constructed and arranged in accordance with my invention. Fig. 2 is an end elevation of the same. Fig. 3 is an enlarged sectional end elevation of the cut-off valve.

In the drawings the reference-numeral 1 indicates the cylindrical casing, carried by a suitable base 2, said casing being supported by a central portion 3. This casing 1 has suitably secured on each side thereof the plates 4 and 5, said plates carrying apertures 6, through which passes a shaft 7, said shaft resting in bearings 8 and 9, which are supported by standards 10 from the base 2. The shaft 7 carries a pulley-wheel 11, from which the power is derived.

The reference-numeral 12 represents square portion carried by the shaft 7, and upon said square portion is mounted a rotary wheel 14, said wheel having recesses formed in its periphery, as indicated at 15, the recesses carrying notches 16 for the reception of a spring 17.

The reference-numeral 18 indicates longitudinal openings in the periphery of the wheel 14, allowing access to the recess 15, and in said opening is mounted the partitions 19. These partitions have their outer ends beveled, the beveled edges extending toward the casing 1, while the other end of said partition rests against the spring 17.

In the upper face of the casing 1 is formed a downwardly-extending portion 21, said portion bearing upon the periphery of the rotary wheel 14 and said portion carrying ports 22 and 23.

In the outer periphery of the casing 1 is formed a steam-inlet 24, communicating with a rotatable cut-off valve hereinafter described, said inlet communicating with the ports 22 and 23, the junction of said ports forming aperture 25, in which is secured a valve 26, said valve seating itself in a seat 27, formed in the portion 21, the valve 26 resting upon the bearing 28, said valve carrying a central stem 29, which passes through packing 30, the stem 29 carrying an operating-lever 31. The valve 26 is formed of two cylindrical portions having an intervening space therein and connected together by an integral partition. The upper cylindrical portion of the valve is formed with apertures and is attached to the stem 29.

In the base of the casing 1 is an exhaust-port 39, said exhaust-port carrying a pipe 40, which passes through an aperture 41, formed in the base portion 3, carried by the base 2.

Attached to the top of the casing 1 and in communication with the steam-port 24 is a rotatable cut-off valve consisting of the casing 42, annular in form and fitted with a head 43 and having a central shaft 44, provided with stuffing-boxes 45. This casing 42 is provided with an opening 47 at the base, 85 registering with the steam-port 24, and at the top fitted with a steam-inlet pipe 24', also with a by-pass pipe 49, having a valve 50 and leading to the steam-port 24. Mounted upon the shaft 44 is a rotatable valve having three arms 46 and portions 46', the latter adapted to close the port 24 when opposite and cut off the supply of steam to the cylinder during a part of the stroke of the rotary wheel 14. Connected to the valve-shaft 44 is a small sprocket - pinion 51, operated by a belt 52, passing over a larger sprocket 53, mounted upon the drive-shaft 7 of the engine, thereby providing a means of giving the valve 46 a continuous rotary movement.

The operation of my improved engine and cut-off valve is as follows: Upon the steam entering the inlet 24' the direction of the engine may be determined by the position of

the reversing-valve 26, and as the valve is shown in the drawings the engine will travel in the direction indicated by the arrows. Upon the steam entering the valve-casing 42 it passes through the port 24, when the same is uncovered and passes downwardly into the cylindrical portion of the engine until cut off by the rotary movement of the said valve, which may be at one-half, one-third, or any part of the stroke, preventing a continuous flow of the steam into the cylinder, thereby getting the benefit of the expansion of the steam, for a purpose well known in the art. The tension of the springs 17, mounted in the recesses 15, has a tendency to eject the partitions outwardly against the cylindrical casing, and upon the steam striking the said partitions the wheel 14 is revolved until said partitions pass the exhaust 39, when the steam will be exhausted. It being desirous to reverse the engine, the valve 26 is turned by means of the handle 31, thus closing the port 23 and opening the port 22. Should one of the portions 46' of the valve 46 cover the opening leading to the port 24 at the time of first starting the engine, the valve 50 is opened, admitting the steam direct to the port 24, and after the engine has been fairly started the said valve closed.

30 Slight modifications and changes may be

made in the details of construction without departing from the spirit of the invention.

Having thus described my invention, what I claim, and desire to secure by Letters Patent, is—

A rotary engine comprising a casing having inlet and outlet ports formed therein, a rotary wheel mounted therein, said wheel having recesses with notches formed therein, the periphery of the wheel having openings formed therein communicating with the recesses, partitions mounted in said openings with springs engaging the inner ends of the partitions, the ends of said springs engaging in said notches, a downwardly-extending portion formed integral with the casing and engaging the periphery of the wheel, oppositely-disposed ports formed in said downwardly-extending portion, a rotatable cut-off valve in communication with the said ports, and a by-pass pipe leading from the steam-inlet pipe to the oppositely-disposed ports, substantially as and for the purpose described.

In testimony whereof I have hereunto signed my name in the presence of two subscribing witnesses.

SIMON S. WHITAKER.
